UNITED STATES PATENT OFFICE.

THOMAS JACKSON, OF NEW CROSS, LONDON, ENGLAND, ASSIGNOR TO HIMSELF, AND
ALLAN RAMSAY, OF FOLKESTONE, ENGLAND.

GAS-METER.

1,123,540.

Specification of Letters Patent.

Patented Jan. 5, 1915.

Application filed April 3, 1914. Serial No. 829,329.

To all whom it may concern:

Be it known that I, THOMAS JACKSON, a subject of the King of Great Britain and Ireland, residing at 7 Milton Court road, New Cross, London, S. E., England, have invented new and useful Improvements in Gas-Meters, of which the following is a specification.

This invention relates to gas meters and has for its object the construction and arrangement of such a device in a simple manner, and at low cost, and having a high degree of accuracy.

This invention consists of an expandible and contractible chamber, the moving wall of which takes up an angular disposition during the expansion and contraction of the chamber which ranges from a + angle with the horizontal line past a point of zero angularity to a - angle with the horizontal line. Upon this moving wall is mounted directly a valve arrangement controlled by gravity during the consequent tilting of the valve box so that the supply of gas and discharge of it from the said chamber are alternately effected. The reciprocating or oscillating motion of the said chamber wall is utilized to operate by means of a ratchet and pawl arrangement or equivalent device, a counting mechanism registering the number of reciprocations and consequently the amount of the gas passed through the chamber. In order to reduce the error of registration or in other words to reduce the lost motion in the transmission gear, teeth of small pitch are used on the ratchet wheel and multiple pawls having a range of disposition of their engaging edges equal to the pitch of the teeth are arranged to act on the ratchet wheel. It will be seen that in this way the angular movement of the wall of the chamber and consequently the change of volume of the same can be accurately transmitted to the counting mechanism.

If only one chamber is used, either gravity or elastic pressure must be employed as a force against which the gas pressure acts in expanding the chamber in order to cause the chamber to contract when the gas supply is cut off and the contained gas is to be delivered for use. If two or more chambers be used they can be arranged to act one against the other so that the incoming gas is used directly to force the outgoing gas from the device instead of this being done

indirectly through the medium of the weight of the moving wall and attendant parts.

In order that the invention may be the better understood, I will now proceed to describe the same in relation to the accompanying drawings, reference being had to the letters and figures marked thereon, like letters referring to like parts in the various figures in which:—

Figure 1 is a view of the simplest form of my invention in which only one expanding chamber is used. Fig. 2 is a view of the invention in the form in which two chambers are used combined in one apparatus. Fig. 3 is a modification in which the two chambers are separate from one another but are connected together by co-acting mechanism.

Referring to Fig. 1 the chamber *a* is provided with the gravity controlled valve and box *b* of the form described and illustrated in the specification of United States Letters Patent No. 1,069,702 to which the supply pipe *d* and delivery pipe *e* are connected. To the movable wall *e* of the chamber *a* is connected a rod *f* which is pivoted to the lever *g* loosely mounted on the axle *h* of the counting train of the meter. The lever *g* pivotally carries one or more pawls *j* which are adapted to engage with the teeth *k* of the wheel *l*. The pitch of the teeth is purposely shown much greater than would be normally used in order to insure clearness of illustration. Any reverse motion of the wheel *l* on the return stroke of the lever *g* is prevented by a series of pawls *m* which are mounted on a fixed pivot and controlled by gravity or other force that can be used for the purpose. In order to vary the relationship between the chamber *a* and the wheel *l* adjusting means such as a slot *n* in the lever *g* are provided by which the leverage can be altered.

In Fig. 2 the chamber *a* is divided into two parts the top wall of which rocks about an axis *o* and two sets of rods *f*, levers *g* and pawls *j* are adapted to operate the wheel *l*.

In Fig. 3 the chambers *a* are entirely separate and are adapted to coöperate by means of a rocking lever *p* pivoted at *q* so that when one chamber is expanding, the other is caused to contract. The action of the rocking valve is clearly shown in the sectional part of Fig. 2 by which the supply

and delivery of the gas is intermittently effected and each volume passed through the chamber *a* is counted by the counting train.

5 What I claim is:—

1. A gas meter having in combination an expansible and contractible measuring chamber having a movable wall, a gravity controlled valve for controlling the admission and exit of gas mounted upon the moving wall of the said chamber, a counting mechanism and means operated by the said chamber wall adapted to register each volumetric movement of the chamber wall, substantially as described.
- 10 2. A gas meter having in combination two measuring chambers having movable walls, a gravity controlled valve carried by each chamber, means adapted to communicate the movement of one chamber wall to the moving wall of the other chamber, a counting mechanism and means by which
- 15

the movement of the chamber wall is transmitted to said counting mechanism, substantially as described.

25 3. A gas meter having in combination an expansible and contractible measuring chamber having a movable wall, a gravity controlled valve for controlling the admission and exit of gas mounted upon the moving wall of the said chamber, a counting mechanism, means operated by the said chamber wall adapted to register each volumetric movement of the chamber wall, and means for varying the relationship of the measuring chamber and the counting mechanism, substantially as described.

30 In testimony whereof I have signed my name to this specification in the presence of two subscribing witnesses.

35 THOMAS JACKSON.
